UNITED STATES PATENT OFFICE.

BRODERICK HASKELL, OF FRANKLIN, PENNSYLVANIA, ASSIGNOR TO DAVIS BRAKE BEAM COMPANY, OF JOHNSTOWN, PENNSYLVANIA, A CORPORATION OF PENNSYLVANIA.

BRAKE-BEAM SUPPORT.

Application filed May 15, 1924. Serial No. 713,488.

To all whom it may concern:

Be it known that I, BRODERICK HASKELL, residing at Franklin, in the county of Venango and State of Pennsylvania, a citizen of the United States, have invented or discovered certain new and useful Improvements in Brake-Beam Supports, of which improvements the following is specification.

10 It is the general practice to employ a length of metal sufficiently long to extend across the truck element and under both brake beams. The invention described and claimed herein relates to certain improvements in the manner of attaching what might be termed independent or individual brake beam supporting rails to a truck element. The invention is hereinafter more fully described and claimed.

20 In the accompanying drawings forming a part of this specification, Fig. 1 is a view partly in section and partly in elevation showing the spring plank of a truck and brake beam supporting rails and embodying 25 the invention claimed herein; Fig. 2 is a top plan view of the construction shown in Fig. 1; and Fig. 3 is a view similar to Fig. 1 illustrating a modification of the improvement.

30 In the practice of the invention the rails 1, 1^a, have their outer portions 2, which underlie the tension member 3 of a truss brake beam, upwardly inclined, and their inner ends firmly secured to the flanges 4 of the 35 spring plank, which may be formed by a channel as shown in Figs. 1 and 2, or by angle bars as shown in Fig. 3.

In the construction shown in Figs. 1 and 2 the inner end of portions of the rails are 40 provided with shoulders 5 and 6 and spaced distances apart substantially equal to the thickness of the flanges 4, 4^a. Thru the flanges are formed openings 7 into which are inserted the ends of the rails to such 45 position that the shoulders 5 will be inside of the flanges. Before inserting the inner ends of the rails, one end of a bar 8 is inserted through the openings in one of the flanges as 4^a sufficiently far to permit of the 50 opposite end being pushed down inside the other flange to a point below the opening 7 in the flange 4. The inner end of the rail 1 is then inserted in the opening in the flange 4 and the bar 8 is shifted longi-

tudinally through the opening in the flange 55 4, the end of the bar passing below the end of the rail forcing it upward so that the shoulders 5 and 6 will bear on opposite sides of the flanges above the opening 7. The movement of the locking and supporting bar to the left is continued until the right hand end thereof is withdrawn from the opening 7 in the flange 4^a. The inner end of the rail 1^a is then inserted into said opening and the bar shifted to the right, 60 the end of the bar passing under the end of the rail and raising it until the shoulders 5 and 6 are in position on opposite sides of the flange 4^a. In Fig. 1 the bar 8 is made of such a length relative to the 65 width of the spring plank that the end portions will extend sufficient distances beyond the sides of the plank to serve as vertical resilient supports for the rails. Provision is made for locking the bar 8 as against 70 longitudinal movement after it has been placed in position as above described. While any suitable means may be employed for locking the bar the device shown consisting of a cotter pin 9 passing through the 75 bar and the web of the spring plank, has been found suitable.

In the construction shown in Fig. 3 openings 7 are formed in the flanges 4 and 4^a as above described for the reception of end 80 portions of the rails 1 and 1^a and the bar 8. In lieu of so constructing the rails so as to engage the flanges of the plank, the rails and bar 8 are so constructed as to interlock 85 one with the other. Such interlocking can 90 be effected by forming a projection or a shoulder on one element and a depression or recess on the other elements for the reception of the projection or shoulder. In the construction shown herein the portions of the bar 8^a extending beyond the sides of the 95 plank have depressions or recesses 10 formed therein for the reception of a projection 11 formed on the brake beam supporting rails. The openings 7 in the flanges are made of 100 a height not substantially greater than the combined thicknesses of the bar and the inner ends of the rails in order to hold said parts in such relation that except under abnormal conditions they will remain interlocked.

In congregating the parts, the bar 8^a is first placed in position then the inner ends

of the rails are inserted through the opening in the flanges and moved longitudinally until the projection on one part enters the depression in the other part, the resiliency of the rails and bar permitting of the movement of one part on the other until interlocking has been effected. It is preferable to ensure the interlocking of the parts by means of links 12 adapted to surround the 10 parts preferably in line with the interengaging depressions and projections. The links are placed on the rails before they are placed in position and then slid along to locking position after the rails have been 15 adjusted.

Suitable means are provided for preventing accidental longitudinal movements of the rails and bar, as for example, by means of shoulders adapted to engage the flanges. 20 In the construction shown, such shoulders 13 are formed by the metal displaced in forming the depression or recesses 10 in the bar 8^a, but as the rails are interlocked with the bar 8^a, it is immaterial whether the 25 shoulders 13 are formed on the bar or rails.

From the foregoing disclosure of its construction, arrangement and manner of assembling and operating the device, it will be seen that all of the objects and advantages recited in the statement of invention 30 have been fully and efficiently carried out and while the preferred forms or modifications of carrying out the invention are shown and described herein, other forms or 35 modifications will readily suggest themselves without in any way departing from the present invention.

I claim herein as my invention:

1. The combination of a flanged spring 40 plank having holes through the flanges, beam supporting rails having their inner

end projecting through said openings and means for locking the rails in position.

2. The combination of a flanged spring 45 plank having holes through the flanges, beam supporting rails having their inner ends projecting through said openings and means for locking the rails in position and means for supporting the rails vertically.

3. The combination of a flanged spring 50 plank having holes through the flanges, beam supporting rails projecting into said holes and provided with spaced shoulders adjacent to their inner ends and means for shifting the ends of the rails laterally to cause 55 the shoulders to bear on opposite sides of the flanges.

4. The combination of a flanged spring 60 plank having holes through its flanges, beam supporting rails having their inner ends projecting into said holes and provided with spaced shoulders adjacent to their inner ends and a bar extending across the plank and passing under the inner ends of the rails and holding such ends in position 45 where the shoulders of the rails bear on opposite sides of the flanges.

5. The combination of a flanged spring 65 plank having holes through its flanges, beam supporting rails having their inner 50 ends projecting into said holes and provided with spaced shoulders adjacent to their inner ends and a bar extending across the plank and passing under the inner ends of the rails and holding such ends in position 55 where the shoulders of the rails bear on opposite sides of the flanges, the outer ends of the bars supporting the rails adjacent to opposite sides of the plank.

In testimony whereof I have hereunto set 60 my hand,

BRODERICK HASKELL.
